UNITED STATES PATENT OFFICE

JOHN W. ASHWORTH, OF NEW YORK, N. Y., ASSIGNOR TO ASHWORTH ADVERTISING COMPANY, INCORPORATED, OF NEW YORK, N. Y., A CORPORATION OF NEW YORK

EXHIBITING SIGN

Application filed April 23, 1929. Serial No. 357,423.

This invention is an exhibiting sign and is constructed to be artificially illuminated. The object of the invention is to provide a construction of marked advertising value 5 and one which will command the attention of passersby.

Speaking generally, the device of this invention embodies a light casing, in the interior of which is positioned a source of illumination. One wall of this casing is transparent or translucent and upon such wall are positioned in vertical sequence letters or characters which it is desired to display. Positioned exterior of the light casing are a 10 plurality of mirrors arranged in angular relation to one another and so disposed that persons approaching the sign from opposite directions will upon looking at the mirrors see projected thereon the letters or characters on the transparent or translucent wall 15 of the light casing. The mirrors and light casing are mounted in a suitable frame which may be in the form of any appropriate standard or may constitute a housing of a weighing scale or other utilitarian object. This standard serves as a support for a frame on 20 which are mounted directional or other display panels adapted to contain any form of information desired, as for example a directory, show cards or other advertising matter.

The device possesses a high degree of merit as an advertising medium and has other 25 utilitarian purposes which will hereinafter be more fully described.

Features of the invention, other than those specified, will be apparent from the herein-after detailed description and claims, when 30 read in conjunction with the accompanying drawings.

The accompanying drawings illustrate different practical embodiments of the invention, but the constructions therein shown 35 are to be understood as illustrative, only,

and not as defining the limits of the invention.

Figure 1 is a perspective view of a device embodying the present invention.

Figure 2 is a perspective view of the modified form of the invention. 50

Referring to the drawings, and more particularly to Figure 1, 1 designates an upright standard shown as embodying a length of pipe although it may be built up structurally of any suitable material. The lower end of the standard is shown as provided with laterally extending feet 2 and a forwardly extending foot 3, the purpose of which is to maintain the standard in upright position. 55

Extending transversely across the upper and lower portions of the standard 1 are bars 4 which are secured by means of rivets, bolts or other suitable means 5 to triangular brackets 6. Spacers 7 are positioned between these parts to space the bars 4 slightly back from the triangular brackets and the brackets are rigidly secured to the standard by means of bolts or rivets 8. Mounted in upstanding position on the upper and lower brackets are mirrors 9 and 10, which by virtue of the substantially 90 degree angle at the apex of each bracket will be at substantially 60 65 70 75 90 degrees to one another.

At the apices of the brackets is secured an upstanding bar 11 on which is mounted a series of electric lights 12. Said bar 11 is slotted along its lateral edges to receive adjacent edges of two transparent or translucent sheets 14 and 15. The sheets 14 and 15 may be made of glass or any other suitable material and on them are delineated letters, characters, symbols or the like designated generally 16 which it is desired to project upon mirrors. The outer lateral edges of the sheets 14 and 15 are provided with corner strips 17 to which are secured the lateral edges of a bowed front plate 18. 80 85 90

This front plate is preferably made of sheet metal and the inner face thereof may be polished to form a reflecting surface adapted to more efficiently concentrate light from the lamps 12 upon the letters 16 in order that they may be projected through the sheets 14 and 15 on to the mirrors 9 and 10, respectively. The parts 11, 14, 15, 17 and 18 constitute collectively a light casing of which the sheets of translucent or transparent material 14 and 15 embody a rear wall.

19 and 20 designate two panels, the upper and lower edges of each of which are provided with grooves to mount them for sliding movement on the bars 4. These panels are in the form of frames in which is provided space for printed matter such as may be appropriate for a directory or for advertising display cards. The panels may be shifted longitudinally of the bars 4 or may be removed therefrom as may be desired.

The structure of Figure 2 is substantially the same as that of Figure 1 with the exception that a weighing scale 21 is associated 25 with the structure already described. The upstanding portion of the scale extends through the triangular brackets, back of the mirrors 9 and 10.

Above the tops of the mirrors is a reading 30 head 21^a of the scale and the base 22 of the scale extends forwardly beneath the bottom of the light casing into accessible position forwardly thereof. The scale is firmly affixed to the standard 1 and thus the necessity for 35 a forwardly supporting leg 3 is obviated because the base 20 of the scale performs the same function. If desired the standard 1 may be extended upwardly to a suitable height and may support a clock or other utilitarian article thereon.

40 In both forms of the invention which I have described, the letters or characters 16 are projected upon the mirrors 9 and 10 so as to be seen by persons approaching from either direction laterally of the sign, while the panels may be observed from the front of the sign and provide convenient display space for any matter which it is desired to exhibit. The device is relatively simple in construction and the arrangement is such as 45 to provide maximum advertising space.

It will be manifest in this regard that the exposed forward face of the wall 18 may contain advertising matter. The device may be used to advantage in a great number of places, such, for example, as in drug stores or other places of business and on the exterior of business establishments or in the hallways or foyers of buildings, hotels, and the like.

60 The foregoing detailed description sets forth the invention in its preferred practical form, but the invention is to be understood as fully commensurate with the appended claims.

65 Having thus fully described the invention,

what I claim as new and desire to secure by Letters Patent is:

1. In an assembly of the character described, a standard, transverse parallel bars extending across the upper and lower portions of the standard, triangular brackets juxtaposed with the bars and secured to the bars and to the standard, mirrors extending between and secured to said brackets, and a vertical light casing secured along its vertical medial line to the apices of both brackets, said light casing having on the walls thereof contiguous to the mirrors characters adapted to be projected on to the mirrors, and a source of light within said light casing. 70 75

2. In an assembly of the character described, a standard, transverse parallel bars extending across the upper and lower portions of the standard, triangular brackets juxtaposed with the bars and secured to the bars and to the standard, mirrors extending between and secured to said brackets, and a vertical light casing secured along its vertical medial line to the apices of both brackets, said light casing having on the walls thereof contiguous to the mirrors characters adapted to be projected on to the mirrors, and a source of light within said light casing, and exhibiting panels supported on the transverse bars laterally of the brackets. 80 85 90

3. In an assembly of the character described, a standard, transverse parallel bars extending across the upper and lower portions of the standard, triangular brackets juxtaposed with the bars and secured to the bars and to the standard, mirrors extending between and secured to said brackets, and a vertical light casing secured along its vertical medial line to the apices of both brackets, said light casing having on the walls thereof contiguous to the mirrors characters adapted to be projected on to the mirrors, a source of light within said light casing, exhibiting panels supported on the transverse bars laterally of the brackets, and a measuring scale, 100 105 110 115

the upright portion of which is secured to the standard, and the base portion of which extends forwardly beneath the light casing to assist in supporting the assembly in upstanding position. 120

4. An exhibiting sign embodying a pair of mirrors arranged side by side and edge to edge and extending rearwardly in divergent relation, a light housing medially disposed at the apex of the mirror assembly, said housing having light penetratable back walls in opposed relation to the respective mirrors, display characters on said back walls, and a source of illumination within the housing to illuminate said characters, whereby they may be seen on the mirrors by persons approaching the sign from opposite lateral directions. 125

5. An exhibiting sign embodying a pair of mirrors arranged side by side and edge to edge and extending rearwardly in divergent 130

relation, a light housing medially disposed at the apex of the mirror assembly, said housing having an opaque front wall and light penetratable back walls in opposed relation to the respective mirrors, display characters on said back walls, said characters being concealed from direct view from in front of the sign by said opaque front wall, and a source of illumination within the housing to illuminate said characters, whereby they may be seen on the mirrors by persons approaching the sign from opposite lateral directions.

10 In testimony whereof I have signed the foregoing specification.

15 JOHN W. ASHWORTH.
